His ATTORNEY

UNITED STATES PATENT OFFICE.

FRANK H. NICHOLSON, OF PHILADELPHIA, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Substitute for application Serial No. 292,127, filed April 23, 1919. This application filed July 26, 1924.
Serial No. 728,438.

To all whom it may concern:

Be it known that I, FRANK H. NICHOLSON, a citizen of the United States, residing at Philadelphia, in the county of Philadelphia and State of Pennsylvania, have invented certain new and useful Improvements in Railway-Traffic-Controlling Apparatus, of which the following is a specification.

My invention relates to railway traffic controlling systems, and particularly to systems of the type wherein alternating currents are supplied to the track rails, and the cars or trains are provided with governing apparatus which is controlled by such currents in the rails. More particularly my invention relates to trackway circuits and apparatus for use in systems of the character set forth.

In one system of the type mentioned, it has been proposed to employ the usual track circuit current, that is, the current which energizes the track relays, as one of the currents for controlling the train carried apparatus, and to supply another current (which I will term the "line current") to the rails of each track section in such manner that it flows in the same direction in the two rails. When this is done, it will be seen that when a track section is occupied by a train, if the line current is of sufficient magnitude and of proper phase, and if it is sufficiently unbalanced in the two track rails in the rear of the train it may cause the track relay for such section to become energized, thus causing a false proceed signal in the rear of the train.

One object of my invention is the provision of means for immediately opening the circuit of the line current for a track section in the event that such current causes energization of the track relay when the section is occupied, thus preventing a false proceed signal in the rear of the train.

I will describe two forms of trackway circuits and apparatus embodying my invention, and will then point out the novel features thereof in claims.

In the accompanying drawings, Fig. 1 is a diagrammatic view showing one form of trackway circuits and apparatus embodying

my invention. Fig. 2 is a view similar to Fig. 1 but showing a modification of the circuits and apparatus illustrated therein.

Similar reference characters refer to similar parts in each of the views.

Referring first to Fig. 1, the reference characters 2, 2^a designate the two track rails of a railway along which traffic normally moves in the direction indicated by the arrow. The rails are divided, by insulated joints 3, into a plurality of sections or blocks, of which only one complete section C—D is shown in the drawing. It is understood, however, that a complete system embodying my invention will usually comprise a plurality of successive sections each of which is equipped with apparatus similar to that shown for section C—D.

Located adjacent the entrance end of section C—D is a roadside signal S^c of the semaphore type, which signal indicates "stop," "caution" or "proceed" according as the semaphore is in the horizontal, inclined or vertical position. A similar signal S^p is provided for the section immediately to the right of section C—D.

The section C—D is provided with a track circuit comprising a source of alternating current (transformer T) and a winding 4 of a polyphase relay H, the source and the relay winding being connected across the track rails at the exit and entrance ends of the section, respectively. Relay H comprises the winding 4, which I will term the "track winding", a second or "local winding" 5, a rotor 6 responsive to currents displaced in phase in the two windings, and two contacts 7 and 8 operated by the rotor. The local winding 5 is supplied (by means not shown) with alternating current of the same frequency as that supplied to the primary of transformer T, but displaced in phase from the current in winding 4 by substantially 90°. The polarity of the track circuit current supplied by transformer T is controlled by a pole changer P actuated by signal S^p.

When this signal is in the proceed or caution position, pole changer P is in such position as to supply current of

- what I will term "normal polarity" to the track rails, in which case the contacts of relay H are swung to the right as shown; but when signal S^p is in the stop position, pole 5 changer P is reversed so that current of reverse polarity is supplied to the track rails, in which case the contacts of relay H are swung to the left. Of course, when track section C—D is occupied by a car or train, 10 the supply of track circuit current from transformer T to the track winding 4 of relay H is discontinued, so that this relay becomes de-energized and contacts 7 and 8 move to the vertical position.
- 15 Signal S^c is provided with a caution circuit and a proceed circuit, which circuits are controlled by contact 7 of the track relay H and by the front point of a contact 10 of a stick relay E. The caution circuit for signal 20 S^c is from one terminal B of a suitable source of current through front point of contact 10 of relay E, wires 14 and 18, and the operating mechanism of signal S^c , to the other terminal O of the same source of current. It will be seen that this circuit is 25 closed only when relay E is energized. The proceed circuit for signal S^c is from terminal B through the front point of contact 10, wires 14 and 15, contact 7 of relay H, wire 17, and mechanism of signal S^c to terminal O. It will be seen that this circuit is closed 30 only when relay H is energized by track current of normal polarity and relay E is energized.
- 35 The stick relay E is provided with a pick-up circuit which is controlled by contact 8 of relay H, and by a contact 13 actuated by signal S^c and closed only when the signal indicates stop. This circuit is from terminal 40 B' of a suitable source of current, through contact 8, wires 19 and 20, contact 13, wires 21 and 23, and winding of relay E to the other terminal O' of the same source of current. It will be seen that this circuit is 45 closed only when signal S^c is in the stop position, and relay H is energized. Relay E is provided with a stick circuit which passes from terminal B' through contact 8, wires 19 and 16, contact 9, wires 22 and 23, and 50 winding of relay E to the other terminal O' of the source of current. This stick circuit, it will be noted, is closed only when relays E and H are both energized.
- 55 Although as here shown the circuits for signal S^c pass from a terminal B of a source of current to a terminal O, and the circuits for relay E pass from a terminal B' of a source of current to a terminal O', it is understood that the terminals B and B', as 60 well as the terminals O and O' are distinguished only to facilitate the matter of tracing the circuits, and that in actual practice the circuits for the signal and for the relay may, and probably will, include one 65 and the same source.

The operation of the apparatus, in so far as the control of signal S^c is concerned, is as follows:

When the track section C—D is unoccupied, and signal S^p is in the proceed or caution position, relays H and E are both energized, relay H being energized in the normal direction, so that signal S^c indicates proceed. If then a car or train enters section C—D, it causes relay H to become de-energized, thereby opening the stick circuit for relay E at contact 8, so that relay E opens. The opening of contact 10 of course causes signal S^c to move to the stop position. As soon as the entire car or train has passed 80 out of section C—D into the section at the right of point D, track relay H becomes energized in the reverse direction, because signal S^p will be at stop and pole changer P reversed. Signal S^c being at stop and contact 13 closed, the pick-up circuit for relay E is closed. As soon as this relay becomes energized, the stick circuit hereinbefore traced becomes effective to hold the relay E in the energized condition as long as track relay H continues to be energized, even though contact 13 is opened by the movement of signal S^c to the caution or clear position. The energization of relay E closes the caution circuit for signal S^c , so that the signal moves to the caution position. When the entire car or train has passed out of the section to the right of section C—D and signal S^p moves to the caution position, the 95 polarity of the track circuit current in section C—D becomes normal, whereupon relay H reverses and signal S^c moves to the proceed position.

Relay E is preferably slow-releasing in character, in order to avoid de-energization of this relay while contact 8 of relay H is swinging from the left to the right hand position, due to change of polarity of the track circuit current when pole changer P reverses.

The trackway apparatus shown herein includes means for causing an alternating line current to flow along the two track rails of the section C—D in the same direction, which current is controlled by traffic conditions in advance. This current is supplied by a transformer U. When signals S^c and S^p are both in the proceed position, as shown in Fig. 1, the path of the line current is from transformer U, through wire 24, contact 25, operated by signal S^p , wire 26, to the middle point of an impedance 27, thence through the two track rails 2 and 2' in multiple to a second impedance 28, from the middle point of which the current flows through wires 29 and 30, contact 12 operated by signal S^c , wire 31, front point of contact 11 of relay E, and wire 32 to transformer U. Contact 12 is closed when signal S^c is in the proceed or the caution position but 100

open when the signal is at stop. When signal S^p is in the caution position, the path of this line current is the same as just traced. When, however, signal S^p is in the 5 stop position, contact 25 is reversed so that wire 24 is disconnected from wire 26 and is connected with a wire 35 which leads to the middle point of an impedance 36; the line current is then supplied to the track 10 rails only between impedances 36 and 28. The circuit for the line current is provided with a branch around signal operated contact 12, which branch is from wire 29, through wire 33, and back point of contact 15 11 of relay E, to wire 32. It will be seen, therefore, that the line circuit is closed when signal S^c is in the stop position, provided that relay E is de-energized.

Before proceeding further, it should be 20 pointed out that the trackway apparatus here shown is intended for cooperation with train carried governing apparatus in the following manner: When the train is on a portion of track which is supplied with 25 track circuit current of normal polarity and also with line current, the governing apparatus permits the train to travel at high speed, such as 60 miles per hour. When the track is supplied with line current, and 30 with track circuit current of reverse polarity, the governing apparatus prevents the train from proceeding at more than an intermediate speed, such as 35 miles per hour, but when the train enters a portion of track 35 from which the supply of either track circuit current or line current has been discontinued, the governing apparatus prevents the train from proceeding at more than a low speed, such as 10 miles per hour. One 40 form of governing apparatus which will cooperate in this manner with the trackway apparatus shown herein, is illustrated and described in Letters Patent of the United States granted on the 7th day of September, 45 1920, No. 1,351,991 to Lloyd V. Lewis, for railway traffic controlling systems.

Assuming now that a car or train has entered section C—D, it will be remembered that the de-energization of track relay H 50 causes stick relay E to open. The closing of the back contact 11 of relay E closes the branch around contact 12 in the circuit for the line current, so that such car or train may proceed through the section under certain speed restrictions determined by the 55 position of signal S^p .

Assuming now that section C—D is occupied by a car or train, and signal S^c is at stop, it is conceivable that owing to a difference in the resistances of the two lines of track rails, such as would be occasioned by a broken rail in one of the lines of track rails behind the train, the line current in the rear of the train may be sufficiently unbalanced in the two rails to cause relay H 60

to become energized. If this occurs, the closing of contact 8 will close the pick-up circuit for relay E, because since signal S^c is at stop, contact 13 is closed; therefore relay E will become energized. The energization of relay E will open the back point of contact 11, thereby cutting off the supply of line current to the rails of section C—D. Since the line current is the only source of energy by which relay H was energized, and 70 since this current is now disconnected from the track rails, relay H will become de-energized, thereby de-energizing relay E. The de-energization of relay E will re-connect the line current to the track rails through 75 the back point of contact 11, and if the line current again energizes track relay H, the 80 operation described above will be repeated.

Should the intermittent action of relays H and E be of such a period that sufficient energy is supplied to signal S^c to move it away from the stop position, the pick-up circuit for relay E will be opened at contact 13, and the intermittent action of 85 relays H and E will cease until signal S^c 90 has returned to the stop position and contact 13 again closed.

It will be noted that by this intermittent action of relays H and E, the train or car in section C—D is intermittently deprived 95 of line current, and this train or car may be compelled to stop, but it will be protected in the rear by the signal S^c at stop. Furthermore, should signal S^c fail to assume the stop position behind a car or train, 100 line current will continue to be supplied to the car or train during its progress through the block.

As soon as the entire car or train passes 105 out of section C—D, track circuit current is again supplied to winding 4 of relay H so that this relay becomes energized and so causes relay E to become energized, whereupon signal S^c moves to the caution position. The pick-up circuit for relay E becomes opened as soon as the signal leaves the stop position, but the stick circuit for this relay has been closed at contact 9, so that relay E continues to be energized. When the signal S^c reaches the caution position, the line circuit for section C—D becomes closed at contact 12. 110

One important feature of the system shown in Fig. 1, is that the circuit for the line current is normally closed when signal S^c indicates caution or proceed, but that this circuit becomes opened intermittently in the event that track relay H is energized by line current while the section is occupied by a car or train. 120

If the pick-up circuit for relay E were controlled only by track relay contact 8, it is possible that when a locomotive or a short train enters the section C—D at high speed, track relay winding 4 might become en- 130

ergized by unbalanced line current and cause the contacts of the track relay to close before signal S^c gets beyond the caution position in its movement from the proceed 5 position toward the stop position. Relays H and E would then both be closed, so that signal S^c would be restrained from further downward movement and it would remain at the caution position or return to the proceed 10 position. The track relay H would then continue to be energized because the line current would continue to flow through contacts 11 and 12. The object of my invention would then be defeated. To avoid 15 such a condition, the pick-up circuit for relay E includes contact 13, so that when the stick circuit for relay E has once been opened at contact 9 due to the entrance of a car or train upon section C—D, it can not again 20 become closed until signal S^c has reached the stop position, wherein contact 12 is, of course, open and relay E can not become energized without disconnecting the line current from the track rails.

25 There may be cases, however, wherein the conditions are such that the provision of contact 13 in the pick-up circuit proves to be unnecessary, and in such cases the arrangement shown in Fig. 2 may be employed.

30 Referring now to Fig. 2, the apparatus and circuits shown therein are the same as those shown in Fig. 1, except for the control of relay E. The stick circuit for this 35 relay is omitted, and the contact 13 is omitted from the pick-up circuit. The operation is substantially the same as that of the apparatus shown in Fig. 1, the only difference being that if relay H should be 40 come energized by line current before signal S^c gets beyond the caution position on its way to the stop position, relay E would become energized at once and would remain energized because the line circuit would then 45 be closed at contact 12 and at the front point of contact 11. The signal would therefore remain at caution or would return to the proceed position.

50 The present application is for the same invention as an earlier application filed by me on the 23rd day of April, 1919, Serial No. 292,127, for railway traffic controlling apparatus.

55 Although I have herein shown and described only two forms of trackway apparatus and circuits embodying my invention, it is understood that various changes and modifications may be made therein within the scope of the appended claims without 60 departing from the spirit and scope of my invention.

Having thus described my invention, what I claim is:

65 1. In combination, a section of railway track, a track circuit comprising a source of

current and a track relay both of which are connected across the rails of said section, a signal for said section controlled by said track relay, a line circuit including the two rails of said section in multiple, said latter 70 circuit having two branches, means for closing or opening one branch according as said signal indicates proceed or stop, and means for opening or closing the other branch according as said track relay is energized or 75 de-energized.

2. In combination, a section of railway track, a track circuit comprising a source of current and a track relay both of which are connected across the rails of said section, an auxiliary relay, a signal for said section controlled by said track relay and by said auxiliary relay, means for energizing said auxiliary relay when said track relay is energized, a line circuit including the two rails 80 of said section in multiple, said latter circuit having two branches, means for closing or opening one branch according as said signal indicates proceed or stop, and means for opening or closing the other branch according as said auxiliary relay is energized or 85 de-energized.

3. In combination, a section of railway track, a track circuit comprising a source of current and a track relay both of which are connected across the rails of said section, an auxiliary relay, a signal for said section controlled by said track relay and by said auxiliary relay, a line circuit including the two rails of said section in multiple, 90 said latter circuit having two branches one of which is closed or open according as said signal indicates proceed or stop and the other of which is closed or open according as said auxiliary relay is de-energized or energized, and means for energizing said auxiliary relay when the signal indicates stop and the track relay is energized.

4. In combination, a section of railway track, a track circuit comprising a source of current and a track relay both of which are connected across the rails of said section, an auxiliary relay, a signal for said section controlled by said track relay and by said auxiliary relay, a line circuit including the two rails of said section in multiple, 100 said latter circuit having two branches one of which is closed or open according as said signal indicates proceed or stop and the other of which is closed or open according as said auxiliary relay is de-energized or energized, and means for energizing said auxiliary relay when the signal indicates stop and the track relay is energized.

105 5. In combination, a section of railway track, a track circuit comprising a source of 110

of current and a track relay both of which are connected across the rails of said section, a signal for said section controlled by said track relay, means for requiring that the signal make a complete movement to the stop position when the track relay becomes de-energized even though the track relay

again becomes energized before such movement is completed, and a line circuit governed by said means and by said signal and including the two rails of the section in multiple.

In testimony whereof I affix my signature.
FRANK H. NICHOLSON.
